LESTER L. JONES, OF ORADELL, NEW JERSEY.

TELEPHONE JACK.

Application filed July 18, 1925. Serial No. 44,463.

To all whom it may concern:

Be it known that I, LESTER L. JONES, a citizen of the United States, and resident of Oradell, in the county of Bergen and State of New Jersey, have invented certain new and useful Improvements in Telephone Jacks, of which the following is a specification.

This invention relates to jack structures, and more particularly to a telephone jack.

A prime desideratum of my present invention comprehends the provision of an improved telephone jack constructed and designed so that the parts thereof, manufactured at low cost, are related so as to be capable of rapid and accurate assembly to produce a jack structure which possesses a number of important advantages in use. More specifically, the objects of the present invention include the provision of a telephone jack in which the supporting, insulating and conducting parts are reduced to a minimum and are coordinated to permit rapid assembly of the parts into a unit in which the conducting elements or spring blades are predeterminedly and accurately spaced; the further provision of a telephone jack in which the spacing of the spring blades is so predetermined during the manufacture of the parts as to permit the assembling operation to be carried out with the use of unskilled help at a small cost; the further provision of an improved telephone jack structure which is designed so as to maintain at a minimum the dielectric leakage between the conducting parts, the latter being so arranged as to be readily connected in circuit; and the still further provision of a telephone jack structure of the type referred to which is strong and durable in construction and neat in appearance.

To the accomplishment of the foregoing and such other objects as may hereinafter appear, my invention consists in the elements and their relation one to the other, as hereinafter more particularly described and sought to be defined in the claims; reference being had to the accompanying drawings which show the preferred embodiments of my invention, and in which:

Fig. 1 is a plan view of my improved tele-

phone jack with a part broken away and showing the same attached to a support such as a panel,

Fig. 2 is a view of the same taken in cross-section on the line 2—2, Fig. 1.

Fig. 3 is a fragmentary view of the same taken in cross-section on the line 3—3, Fig. 1,

Fig. 4 is an enlarged view of the same taken in cross-section on the line 4—4, Fig. 2, and

Fig. 5 is a view of parts of the same showing a modified form thereof.

Referring now more in detail to the drawings, the telephone jack structure of my invention comprises a bracket generally designated as 10, a pair of mating insulating blocks 11 and 12 arranged in superposed relation on the bracket 10, and a plurality of jack spring blades or leaves 13, 13 of any desired number mounted between and arranged transversely of said blocks, with the planes of the jack blades or leaves lying normal to the plane of the bracket 10, the said jack blades being clamped between the insulating blocks 11 and 12 and the latter being joined together and secured to the bracket 10 by means of the securing element 14.

The bracket 10 comprises in its most simple form an angle or L-shaped member having a leg portion 10^a which carries the parts of the jack structure, and a foot portion 10^b to which is secured the usual panel mounting thimble 15 which threadedly receives the nut 16 for mounting the jack structure on a support such as a panel 17, the thimble serving for receiving and guiding the usual jack plug 18 into operative position, as clearly shown in Fig. 1 of the drawings.

The mating insulating blocks 11 and 12 are designed and constructed so as to permit rapid and to facilitate correct assembly of the jack blades or leaves, and so as to minimize the surface dielectric leakage between the blades, especially after the leads or conductors are soldered thereto. In accordance with one well-known method of telephone jack manufacture, the blades are arranged in vertical superposition separated by insulating sheets, the separation between the

blades being determined by the thicknesses of the insulating sheets. These insulating separators are usually punched from thin sheet stock, and present a great deal of 5 semiporous end grain into which the solder flux flows when the leads are attached to the spring blades, forming a hygroscopic surface producing considerable surface leakage, especially in humid weather. The stock 10 from which the separators are punched is of non-uniform thickness, and hence the correct separation between the blades is difficult to obtain. Moreover, the assembly of the 15 spring blades and insulating separators produces crevices into which the flux has a tendency to flow, thus further reducing the dielectric resistivity between the jack springs. The insulating blocks 11 and 12 of my invention are so designed as to obviate these 20 advantages; and to accomplish the desired results, the mating blocks 11 and 12 are made of a molded insulation material producing outer walls having an impermeable hard smooth finish, into which the flux can- 25 not penetrate, and which impermeable walls may be readily cleaned to increase the surface resistivity between the springs, the mating blocks being provided with pairs of mating notches 19 and 20 produced during the 30 molding operation, each pair of notches being designed for receiving a jack spring 13. By means of this construction, it will be seen that the separation between the jack blades may be accurately predetermined for facil- 35 itating the rapid and correct assembly of the blades, and that the surface dielectric leakage between the blades may be maintained at a minimum by the provision of the hard impermeable molded finish of the 40 insulating surfaces.

To further assist in permitting rapid assembly of the parts and to eliminate securing elements, the spring blades 13 are fixed to and clamped between the insulating 45 blocks 11 and 12 with a dovetailing fit, the spring blades 13 and the mating notches 19 and 20 being contoured to produce the dovetailing interengagement between the parts. More specifically each of the spring blades 50 13 is provided with a portion 13^a receivable by a pair of the mating notches 19 and 20, the said portion 13^a being contoured to provide the top and bottom notches 21 and 22 and the insulating blocks 11 and 12 being 55 contoured to provide integral tongues 23 and 24 which dovetail with the spring blade notches 21 and 22 respectively. Preferably the insulating block notches 19 and 20 of each pair are oppositely tapered with the 60 larger bases of the tapered portions adjoining, as clearly shown in Fig. 4 of the drawings, and the clamping portions 13^a of the spring blades are crimped as shown particularly in Figs. 1 and 4 of the drawings, so 65 that the jack blades are received by the in-

sulating blocks with a secure clamping as well as a dovetailing fit, a rigid mounting of the jack blades being thereby produced.

To keep the number of parts down to a minimum so as to reduce the cost of manufacture and to further aid in permitting rapid assembling operation, a single securing element 14 is utilized for joining the blocks together and for attaching the same to the bracket 10, the said securing element 70 14 extending through the said blocks and being threadedly attached as at 25 to the bracket leg 10^a. To permit the use of a single securing element, the lower insulating block 12 and the bracket 10 are provided 75 with integral mating elements designed to fix the blocks to the bracket against rotation, and preferably the lower insulating block 12 is provided with one or more integral stud portions 12^a, preferably four in number, as 80 shown particularly in Figs. 1 and 3 of the drawings, the said studs being receivable by 85 complementary apertures 10^c, 10^e provided in the bracket 10.

In Fig. 5 of the drawings, I show a modification of the pair of insulating blocks designed so as to further reduce the surface leakage between the jack blades. In this modification, the insulating blocks 11' and 12' are constructed so that the outer walls 90 only contact or engage, the inner projections between the mating notches being separated by an air space.

The method of making, assembling and using the improved jack structure of my present invention and its many advantages will in the main be fully apparent from the above detailed description thereof. It will be apparent that with the jack spring blades arranged transversely of the jack structure, 100 with the planes of the blades lying normal to the plane of the bracket, the number of blades or leaves used may be comparatively large and may be arranged symmetrically on both sides of the axis of the bracket without interference, this construction furthermore permitting ready accessibility to the individual leaves or blades for soldering leads thereto. All of the spring blades are held between a pair only of molded insulated 105 pieces, thus reducing the number of insulating separating members to a minimum and permitting rapid and accurate assembling of the jack springs thereon. The insulating blocks are so constructed and related to the supporting spring blades as to minimize the crevices and as to produce a hard smooth-surface finish, the construction being such that the surface leakage between the spring blades is reduced to a minimum. The provision, moreover, of the insulating blocks provided with the positioning studs, further permits the use of a single securing device for assembling all of the parts in 110 secured relation, and aids in facilitating the 115 120 125 130

assembly positioning of the parts on the bracket. By means, therefore, of the inter-related elements as described, I am enabled to produce a telephone jack structure capable of simple processes of manufacture and assembly and possessing highly advantageous properties in use.

While I have shown my invention in the preferred forms, it will be obvious that many changes and modifications may be made in the structure disclosed without departing from the spirit of my invention, defined in the following claims.

I claim:

- 15 1. A telephone jack structure comprising a bracket having means for attaching the same to a panel, a pair of mating insulating blocks arranged in superposed relation on said bracket, a plurality of jack spring 20 blades mounted between and arranged transversely of said blocks with the planes of the blades lying normal to the plane of said bracket, the said insulating blocks being provided with pairs of mating notches and 25 each of said jack blades having a portion receivable with a dovetailing interengagement by a pair of such notches for securing such blade to and between the insulating blocks, the said bracket and the lower of 30 said blocks being provided with mating elements for positioning the blocks on the bracket, and a securing member joining the blocks together and attaching the same to the bracket.
- 35 2. A telephone jack structure comprising a bracket having leg and foot portions, a panel mounting thimble attached to the foot of said bracket, a pair of mating insulating blocks arranged in superposed relation on 40 the leg of said bracket, a plurality of jack spring blades mounted between and arranged transversely of said blocks with the planes of the blades lying normal to the plane of said bracket leg, the said insulating 45 blocks being provided with pairs of mating notches, each of said jack blades having a portion receivable with a dovetailing fit by a pair of said notches for securing such blade to and between the insulating blocks, the said bracket leg and the lower of 50 said blocks being provided with integral mating elements for fixing the blocks in position on the bracket, and a unitary securing element extending through said blocks and threadedly attached to said bracket leg for joining the blocks together and securing the same to the bracket.
- 55 3. A telephone jack structure comprising a bracket having means for attaching the same to a panel, a pair of mating impermeable smooth faced blocks made of molded insulation material arranged in superposed relation on said bracket, a plurality of jack spring blades mounted between and arranged transversely of said blocks with the

planes of the blades lying normal to the plane of said bracket, the said insulating blocks being provided with pairs of oppositely tapered mating notches, each of said jack blades having a portion receivable with 70 a dovetailing and clamping fit by a pair of such notches for securing such blade to and between the insulating blocks, and a securing member joining the blocks together and attaching the same to the bracket.

4. A telephone jack structure comprising a bracket having leg and foot portions, a panel mounting thimble attached to the foot of said bracket, a pair of mating insulating blocks arranged in superposed relation on the leg of said bracket, the lower of said blocks having an integral stud mating with a positioning aperture in said bracket leg, a plurality of jack spring blades mounted between and arranged transversely of said blocks with the planes of the blades lying normal to the plane of said bracket leg, the said insulating blocks being provided with pairs of mating notches, each of said jack blades having a portion receivable with a dovetailing fit by a pair of said notches for securing such blade to and between the insulating blocks, and a single securing element extending through said blocks and threadedly attached to said bracket leg for joining the blocks together and securing the same to the bracket.

5. A telephone jack structure comprising a bracket having leg and foot portions, a panel mounting thimble attached to the foot of said bracket, a pair of impermeable smooth faced mating blocks made of a molded insulation material arranged in superposed relation on the leg of said bracket, the lower of said blocks having a plurality of integral studs mating with positioning apertures in said bracket leg, a plurality of jack spring blades mounted between and arranged transversely of said blocks with the planes of the blades lying normal to the plane of said bracket leg, the said insulating blocks being provided with pairs of oppositely tapered mating notches, each of said jack blades having a portion receivable with a dovetailing and clamping fit by a pair of said notches for securing such blade to and between the insulating blocks, and a single securing element extending through said blocks and threadedly attached to said bracket leg for joining the blocks together and securing the same to the bracket.

6. A telephone jack structure comprising a bracket having means for attaching the same to a panel, a pair of impermeable smooth-faced mating blocks made of a molded insulation material arranged in superposed relation on said bracket, a plurality of jack spring blades mounted between and arranged transversely of said blocks with

the planes of the blades lying normal to the plane of said bracket, the said insulating blocks being provided with pairs of mating

and a securing element joining the blocks together and attaching the same to the bracket.

5 notches, each of said jack blades having a portion receivable with a dovetailing fit by a pair of said notches for securing such blade to and between the insulating blocks,

Signed at New York city in the county of New York and State of New York this 16th day of July, A. D. 1925.

LESTER L. JONES.
